FORK

Donald Wallace, Croton-on-Hudson, N.Y., assignor to
H. E. Lauffer Co., Inc., Somerset, N.J.

Filed July 25, 1972, Ser. No. 274,879

Term of patent 14 years

Int. Cl. D7—03

U.S. Cl. D7—137

FIG. 1. FIG. 2. FIG. 3. FIG. 4.

FIG. 5. FIG. 6.

FIG. 7.

FIG. 8.

FIG. 1 is a top view of a fork showing my new design;
FIGS. 2 and 4 are left and right-hand side views
thereof;

FIG. 3 is a bottom view thereof;

FIG. 5 is a front end view thereof looking in the direction from the tines toward the handle portion;

FIG. 6 is a rear end view thereof looking in the direction from the handle portion toward the tines;

FIG. 7 is a sectional view thereof looking in the direction of arrows 7-7 of FIG. 1; and

FIG. 8 is a sectional view thereof looking in the direction of arrows 8-8 of FIG. 1.

I claim:

The ornamental design for a fork, as shown.
